SECRET
Walter Hill
Samuel L. Reid

Walter S. Hill, and Samuel T. Reed, of New York, N.Y.
Letters Patent No. 1658, dated Sept. 23, 1862,

The schedule referred to in these Letters Patent and making part of the same,

To all whom it may concern:

Be it known that we, Walter S. Hill and Samuel T. Reed, of the City, County and State of New York, have invented or produced a new and improved design for a Chess and Checker Board; and we do hereby declare that the following is a full, clear and exact description of the same, reference being had to the accompanying drawings making a part of this specification, said drawing being a facsimile of a chess and checker board showing our design.

This design consists in providing the squares of the chess and checker board with portraits every alternate square being contrasted with the intermediate ones by a dark back ground.

In the accompanying drawing, it will be seen that the portraits a, have a light back ground and are in alternate squares while the intermediate squares b, have a dark or black back ground.

The portraits at each side of the chess or checker board, that is to say those on the square on which the pieces of each player are originally placed at the commencement of the game, have the portraits so disposed as to face the player. The portraits of the squares at one side being in a reverse position to those at the other side as plainly shown in the drawing.

Having thus described our invention what we claim as new and desire to secure by Letters Patent: is -

A chess and checker board having its squares provided with portraits as shown and described to form a new and original design for the same.
